UNITED STATES PATENT OFFICE.

ANDREW J. BENTON, OF WASHINGTON, DISTRICT OF COLUMBIA, ASSIGNOR TO LANSTON MONOTYPE MACHINE COMPANY, OF PHILADELPHIA, PENNSYLVANIA, A CORPORATION OF VIRGINIA.

LEADING OR SLUGGING DEVICE.

No. 889,893.

Specification of Letters Patent.

Patented June 9, 1908.

Application filed February 19, 1907. Serial No. 358,176.

To all whom it may concern:

Be it known that I, ANDREW J. BENTON, a citizen of the United States, residing at 310 E street northeast, in the city of Washington, 5 ton, District of Columbia, have invented certain new and useful Improvements in Leading or Slugging Devices, of which the following is a full, clear, and exact description, reference being had to the accompanying drawings, and the figures of reference marked thereon, which form a part of this specification.

This invention relates to means for automatically supplying leads in conjunction 15 with lines of type as produced or set up in composing machines, and it consists in the several novel features of construction and combinations and arrangements of parts hereinafter described and pointed out in the 20 claims.

In the accompanying drawings—Figure 1 is a top plan view of the attachment as specially adapted for use in connection with the well known Monotype type casting machine. Fig. 2 is a vertical section. Fig. 3 is a rear perspective of a portion of the feeding devices.

Similar numerals designate like parts in the several figures.

30 The improvements are illustrated in a form specially adapted for application as an attachment to the type composing machine of Patent No. 625,998, of May 30, 1899, generally known as the Monotype casting machine, but is applicable to other forms of composing machines. Only those parts of the composing machine with which the improvements are immediately associated are shown in the drawings, such as the galley 35 frame 1 and galley blade or rule 5, and as an aid to a clear understanding of the operation of apparatus about to be described it may be remarked that the galley blade is located at the mouth or entrance to the galley between the latter and the line pusher or trans- 40 ferrer, the arrangement being such that after an assembled line of type is delivered opposite the entrance to the galley in the interval between the line pusher and galley blade, 45 the latter is raised and the line pusher is advanced to force the assembled line of type beneath the elevated galley blade into the galley, whereupon the galley blade descends sufficiently to engage and support the line 50 of type and the line transerrer is retracted,

followed by the descent of the galley blade to first position.

At a suitable point on the galley frame 1 is erected a column or support 8 provided at its upper end with a horizontal extension or plate 7 forming the bottom of a magazine or holder for the reception of a column of leads 10. The opposite ends of this magazine are formed by U-shaped bars 9 mounted upon plate 7. The flanges of bars 9 are cut away 60 at the lower ends next the plate 7 to form a delivery gate for the passage of the lowermost lead on the one side and a guide way for a pusher or ejector blade 14 on the other, 65 said blade being connected by a link or links 13 to an arm or arms 12 on a rock shaft 17, the latter supported in bearings 15 secured to plate 7 and provided with one or more slotted actuating arms 6.

Supported at its lower end upon the galley 70 blade 5 to move with the latter is an inclined delivery chute comprising two parallel side bars 2 flanged on their upper and lower edges to form U-shaped channels and connected rigidly by cross bars or braces 3. 80

The lower ends of the bars 2 together with their flanges are curved to bring that end of the chute into parallel with the galley blade, the upper flanges being off-set so that their inner faces will align with or project slightly 85 beyond the face of the galley blade next the galley, and, in addition the bars 2 are provided with a supplemental galley blade in the form of a plate 4 fastened to and carried by said bars in alinement with the inner 90 flanges of said bars. Thus the galley blade 5 and supplemental galley blade 4 form a continuation or prolongation of the delivery chute for directing the lead into position in rear of the galley blade 5, and in addition 95 said supplemental galley blade 4 operates in place of the normal galley blade to support the line of type last delivered to the galley. The upper flange plates of bars 2 are bent or curved upwards or away from said bars, and 100 to the plate 7 on the delivery side of the magazine is hinged a cut-off plate 18, the outer or free edge of which engages or rests upon the upper ends of the under flange plates of bars 2. When the chute is in its 105 lower position plate 18 uncovers the entrance to the chute and forms a continuation of the under flanges over which the leads are conducted from the delivery gate of the feeder to said chute; when, however, the chute is ele- 110

vated the cut-off plate 18 turning upon its pivot swings across and closes the entrance to the chute, at the same time presenting a support for the reception and retention of the lead delivered thereon, until, upon the next descent of the chute, it swings down into alinement with the lower flanges and permits the lead to enter the chute. The upper ends of bars 2 are supported to both oscillate and 10 reciprocate, to which end each is mounted in a guideway on a block or bearing 19 pivotally attached to the outer face of one of the magazine bars 9, and one or both of said bars 2 is equipped with a removable or retractable pin 20 engaging the slot in the corresponding arm 6 of the ejector blade actuating devices.

To accommodate the attachment to deal with leads of different lengths one or both of the side bars 9 may be equipped with a movable section 9' supported by adjusting screws 16 passing through bar 9, and, in like manner, either or both of the bars 2 may be provided with U-shaped sections connected to said bars by similar adjusting screws 16.

25 Operation: With the galley blade down and closing the entrance to the galley, ejector blade 14 stands in retracted position in rear of the lowermost lead in the magazine and cut-off plate 18 rests upon the lower flanges 30 of the delivery chute. As the galley blade is elevated, to admit an assembled line to the galley, the delivery chute is both raised and tilted and by its movement cut-off plate 18 is tilted, to close the entrance to said chute 35 and at the same time pin 20 riding in the slot in arm 6 of shaft 17 turns the latter and through arm 12 and link 13 the ejector blade 14 is advanced to discharge the lowermost lead from the magazine and deliver it upon 40 the cut-off plate. The lead is retained by the cut-off plate during the partial descent of the galley and supplemental galley blades, incident to the withdrawal of the line pusher, but during the final movement of said blades 45 the cut-off plate is withdrawn, by permitting its free edge to descend, and the lead sustained thereby is discharged into the delivery chute and conducted by the latter into the interval between the two galley blades, in 50 position to be advanced into the galley by the next succeeding assembled line when the galley blades are again elevated for the purpose.

When access to the galley mechanism is 55 desired the delivery chute can be moved out of the way by simply detaching and elevating its lower end, and to interrupt the delivery of leads it is only necessary to withdraw the connection 20 from arm 6 in which case the 60 delivery chute may be either withdrawn from its pivoted bearing blocks 19 or swung thereon and be maintained in inoperative position by the application of suitable means, such as a hook, stop pin or equivalent retaining 65 vice.

It is to be noted that the leading mechanism described constitutes a complete self contained attachment and is adapted to be applied to existing composing machines without further change in or addition to the 70 mechanism thereof in the way of actuating or accommodation devices, and without interference with its normal functions, the only condition being the provision of an adequate support for the frame or column 8. 75

Having thus described my invention, what I claim as new and desire to secure by Letters Patent, is:

1. In combination with the movable galley blade of a composing machine such as 80 described, a self contained leading attachment including a support, a feeding mechanism and a delivery chute the latter coupled with the galley blade and feeding devices for transmitting motion from one to the other. 85

2. In combination with the movable galley blade of a composing machine such as described, a self contained leading attachment provided with an oscillatory delivery chute engaging said galley blade, a supplemental galley blade carried by said chute, and a magazine and a lead feeding mechanism the latter coupled with and actuated by the delivery chute. 90

3. In a leading attachment for composing 95 machines, the combination of the following elements, to wit; a magazine; an ejector; and a delivery chute pivotally supported and coupled with the ejector to actuate the latter.

4. In a leading attachment for composing machines, the combination of the following elements, to wit; a pivotally supported delivery chute; a magazine provided with a delivery gate or passage; an ejector opposite said delivery gate or passage; and actuating devices for said ejector coupled with the delivery chute. 105

5. In a leading attachment for composing machines, the combination of the following 110 elements, to wit; a pivoted delivery chute provided with a supplemental galley blade; and a feeding mechanism delivering leads to said chute.

6. In a leading attachment for composing 115 machines the combination of the following elements, to wit; a pivoted delivery chute; a lead feeding mechanism and a cut off.

7. In a leading attachment the combination of the following elements, to wit; a pivoted delivery chute; a feeding mechanism; and a cut-off the latter receiving the leads from the feeding mechanism and delivering them to the delivery chute. 120

8. In a leading attachment the combination of the following elements, to wit; a feeding mechanism; a cut-off to which the leads are delivered; and a pivoted delivery chute coupled with and actuating said cut-off and feeding mechanism. 125 130

9. A leading attachment for composing machines, the same including, in combination, a supporting frame, a magazine, provided with a delivery gate; an ejector; 5 movable delivery chute; and a cut-off intermediate said chute and the delivery gate of the magazine.

10. A leading attachment for composing machines such as described, the same including, in combination, the following elements, to wit; a frame; a delivery chute pivotally supported on said frame and adapted to engage a movable member of the composing machine; a plate pivotally supported upon 15 the frame and movable across the receiving end of said chute; a feeding device for the leads mounted upon said frame and delivering upon said pivoted plate; and means for actuating said feeding devices and pivoted 20 plate by the movement of the delivery chute.

11. In a leading attachment for composing machines, the combination of the following elements, to wit; a pivoted delivery chute adapted to engage a movable member of the 25 composing machine; a lead feeding mechanism mounted upon a supporting frame;

and actuating devices for said feeding mechanism coupled with the delivery chute and including a detachable transmitting member.

12. In a leading attachment for composing machines and in combination with the frame thereof a magazine provided with a delivery gate and an ejector; a delivery chute mounted to reciprocate longitudinally in bearings, the latter pivotally connected to the magazine; and actuating devices for the ejector including separable transmitting members. 30 35

13. A leading attachment provided with a magazine and ejector and in combination therewith a pivoted delivery chute adapted 40 to engage a movable member of a composing machine and provided with connected flanged side bars; and a cut-off comprising a hinged plate whose free edge engages the lower flanges of the side bars. 45

In testimony whereof I affix my signature in presence of two witnesses.

ANDREW J. BENTON.
